UNITED STATES PATENT OFFICE.

BURTON U. HILLS, OF CHICAGO, ILLINOIS.

ACCELERATOR.

Application filed February 27, 1922. Serial No. 539,611.

To all whom it may concern:

Be it known that I, BURTON U. HILLS, a citizen of the United States, residing at Chicago, in the county of Cook and State 5 of Illinois, have invented certain new and useful Improvements in Accelerators, of which the following is a description.

My invention relates to means adapted to be manipulated by the driver's foot for controlling the throttle of a driving motor of a motor vehicle to control the operation of the vehicle, and the same also preferably includes a simple foot rest and guide for accurately determining the position of the 15 driver's foot upon the controlling mechanism.

The invention has among its objects the production of an accelerator of the kind described which can be used entirely independent of the ordinary hand throttle commonly found on motor vehicles without disturbing or affecting the position of said hand throttle, permitting said hand control to be used in conjunction with or independently of the said accelerator whenever desired.

A further object is to produce an accelerator of the kind described that may be easily and conveniently installed, and which is applicable for different styles or kinds of carburetors.

Another object of my invention is to produce a device of the kind described which is convenient, compact, durable, reliable, efficient and satisfactory for use wherever found applicable.

Many other objects and advantages of the construction herein shown and described will be obvious to those skilled in the art 40 from the disclosures herein given.

To this end my invention consists in the novel construction, arrangement and combination of parts herein shown and described, and more particularly pointed out in the 45 claims.

In the drawings, wherein like reference characters indicate like or corresponding parts,

Fig. 1 is a plan view of my device as applied to a well known type of motor vehicle, as viewed from above;

Fig. 2 is a side elevation of the same;

Fig. 3 is an enlarged section taken substantially on the line 3—3 of Fig. 2;

Fig. 4 is a similar section taken substantially on the line 4—4 of Fig. 1;

Fig. 5 is a similar section taken substantially on the line 5—5 of Fig. 2;

Fig. 6 is a section taken substantially on the line 6—6 of Fig. 4;

Fig. 7 is a top plan view of a portion of my device showing its manner of attachment to the steering column;

Fig. 8 is an enlarged section taken substantially on the line 8—8 of Fig. 2;

Fig. 9 is a section taken substantially on the line 9—9 of Fig. 7, and

Fig. 10 is an enlarged section taken substantially on the line 10—10 of Fig. 2.

In the drawings, wherein I have shown the preferred form of my invention, 1 indicates an internal combustion engine, 3 a carburetor connected to the intake manifold thereof, and 2 the foot board of the motor vehicle, all of the same representing the usual or any suitable arrangement and construction. There is also shown a steering column 4, through which extend the rods 5 and 6, and a central column 7, this being of the usual construction in the type of vehicle illustrated. In this construction, column 7 is operatively connected with the steering wheel (not shown), and controls the front wheels during the steering, while the rod 6 controls the throttle and rod 5 the ignition mechanism, these two latter rods being adapted to be manually operated in the usual way at a point near or adjacent the steering wheel, which, as before mentioned, is not shown.

A foot-operated or accelerator rod 8 is connected to intermediate mechanism carried by a bracket or supporting means 9 mounted on the column 7 and carried thereby, said mechanism being operatively connected through a throttle rod 10 with the carburetor throttle, as shown in Fig. 3. The construction is such that the throttle rod 10 may also be controlled by the rod 6.

The foot rod 8 extends, in the construction shown, to and through the foot board 2, and is provided with an enlarged head or knob 11 at the end thereof, arranged to be conveniently engaged by the foot of the driver. The rod preferably is arranged so that it may be moved lengthwise through the floor board in operation. I have shown a foot plate 12 mounted on the floor board 2 and provided with an opening 15 through which the rod 8 extends. Generally I prefer to make the foot plate in the form of an L, with a portion 13 thereof extending trans-

versely from the part 12 and away from the floor board 2. The plate 12 may be secured to the floor board by screws 14 or any equivalent means for the purpose. 5 There may be and is preferably provided a foot rest or support 17, which in the construction shown consists of a threaded bolt (see Fig. 10), provided with an enlarged head 18 and positioned in a threaded hole 10 16 through the plate 12. This construction permits adjustment of the support so that the same may be fitted to the driver. After being adjusted, the same may be locked in the adjusted position by the nut 19, or 15 equivalent means for the purpose. This adjustable feature permits the operator to so regulate the height of the support that a maximum degree of comfort and convenience may be secured. In use the head 18 20 serves as a fulcrum for the operator's foot, while the extending portion 13 serves as a guide and accurately locates the foot in relation to the head 18, and the head 11 on the accelerator rod 8. Obviously any equivalent 25 structure may be employed for the purpose.

The accelerator bracket or support 9, which forms the support and carries the connecting mechanism between the rods 8 and 10, consists of clamping plates or members 30 20 and 21, which preferably are constructed to interengage, as well as to embrace and be secured on the parts 5, 6 and 7. As shown, the plates are mounted on the parts and may be secured in place by bolts 22 or the equivalents, spacers 23 being positioned on the bolts between the plates 20 and 21 so as to prevent the rods 5 and 6 from being locked against movement when it is desired to rock them back or forth to control the throttle 40 or ignition apparatus. One of the parts of the bracket 9, as shown part 20, is provided with an extending side portion 24, which carries a part of the intermediate connecting mechanism to be hereinafter described, and 45 there is also provided an extending part or ear 31, which likewise carries a portion of the intermediate connecting mechanism.

To align the parts and maintain them 50 against relative movement, I have arranged the two plates so that they interengage. As shown, openings 25 are provided in the side portion 24 of the plate 20 arranged to operate with tongues or lugs 26 provided on the other part and projecting into the openings. At the opposite side the plate 20 is notched or cut in, as indicated at 25', and the plate 21 is arranged at 26' to engage 55 thereat.

The support 9 is positioned on the steering column, with one end abutting against the throttle arm 27 carried on the rod 6. At the opposite end of the support I arrange a collar 28, or the equivalent, on the rod 6, for preventing movement in that direction. The collar illustrated is open at one

side, so that it may be positioned on the rod 6 without the necessity of disconnecting the rod and sliding it therewith from one end. It may be secured in place by a setscrew 29, or equivalent means. Generally 70 I prefer to provide a corrugation or rib 30 on one or both of the support members, in the present instance the same being shown on the plate 20 and of a length to extend downwardly on the part 24, thereby stiffening the same and permitting material of substantially light weight to be employed for the bracket. The bracket or support carries two connected bell crank levers 33-34, and 75 39-40, the two being mounted and movable in planes transversely to each other. Referring particularly to Figs. 4 and 5, bell crank 33-34 is pivotally secured to the ear 31 by pin 32, or the equivalent, the same being movable in a plane transversely of the 80 steering column. Arm 34 of the bell crank lever is provided with an offset extension 35 projecting in the path of movement of the throttle arm 27, as shown in Figs. 1, 3 and 4. At the end of the arm 34 is arranged a link 36, which is adjustably secured to the arm by a small bolt 38 or its equivalent, the free end of the link being pivotally connected to the throttle rod 10, so that movement of the bell crank lever will control 85 the movement of the throttle rod 10 and the carburetor throttle. By adjustably securing the link 36 to the arm 34, the same may be adjusted as desired, so as to make the device applicable to different makes of carburetors. Varying the adjustment of the link obviously varies the connection of the 90 throttle rod and the bell crank lever arm. This is of importance and a desirable feature and affords considerable variation in 95 installation.

The bell crank lever with arms 39-40 is pivotally mounted on the pivot pin 41, carried on the extension 24, this arm being movable in a plane substantially paralleled with the steering column and with the foot rod or transversely to the movement of the bell crank lever 33-34 or throttle rod 10. The arms 33 and 40 of the bell cranks are connected by a link 42, or the equivalent, 100 in any suitable manner. As shown by ball and socket joints so that they are universally movable, the links being provided with the balls or spherical ends 43 and the arms provided with socket members 44. Obviously movement of rod 8 and pivotal movement of the bell crank lever 39-40 in one plane 105 will be transmitted to provide a pivotal movement of the bell crank lever 33-34 and rod 10 in a plane transversely thereto. Suitable means are preferably provided for returning the parts to normal position when the foot is removed from the head 11 at the end of the accelerator rod 8. As shown, a spring 45 mounted on the pivot pin 41 en- 110

gages the extension 24 and the arm 39 and tends to maintain the parts in inoperative position so that when the accelerator rod 8 is moved and then released, the parts tend 5 to return to their initial position. The rod 8 may be connected to the arm 39 in any suitable manner. As shown, a head 46 is pivoted or swiveled on the end of the arm, the same having an opening 47 therethrough 10 adapted to receive the end of the rod 8. Nuts 48 on opposite sides of the head and mounted on the rod secure the parts together. Obviously the effective length of the rod may be varied by adjusting the connection at the head 46.

From the preceding description it will be seen that operation of the foot rod 8 by the operator upon depression of the head 11 will cause a lengthwise movement of the 20 foot rod, which will be transmitted through the connecting mechanism, including the bell crank levers and links to the throttle rod 10, moving the same lengthwise, and this being connected to the throttle of the car- 25 buretor controls the operation of the engine. The foot rest and guide previously described enables the operator to easily find the accelerator rod end and afford a support for the foot, enabling the accelerator to be 30 manipulated smoothly, even on rough roads. It will be particularly noted that with this construction, while the throttle rod may be operated easily and conveniently by the throttle rod 6 on the steering column and 35 from the steering wheel, no movement will be transmitted to the throttle rod 6 and lever on the steering wheel when the accelerator control is used. The device does not require any re-arrangement of the mechanism already installed on the car, but is 40 supplemental thereto.

It is not considered necessary to set forth in detail all the advantages of the construction from the viewpoint of the user, nor is it deemed necessary to describe all the various modifications or adjustments that are 45 possible. It will be noted that the device is simple in construction and may be installed by anyone without requiring the assistance of a skilled mechanic.

Having thus described my invention, it is obvious that various immaterial modifications may be made in the same without departing from the spirit of my invention; 50 hence I do not wish to be understood as limiting myself to the exact form, construction, arrangement and combination of parts herein shown and described or uses mentioned.

60 What I claim as new and desire to secure by Letters Patent is:

1. In a device of the kind described and in combination, a pair of bell-crank levers, a throttle rod, an operating rod, one of 65 said levers connected to one of said rods

and the other to the other rod, means for mounting said levers on a steering post, and universally movable connecting means operatively connecting said levers, whereby they will be operated pivotally in unison. 70

2. In a device of the kind described and in combination, a pair of bell-crank levers, a throttle rod, an operating rod, one of said levers connected to one of said rods and the other to the other rod, means for pivotally mounting said levers in mutually 75 transverse planes on a steering post, and universally movable connecting means operatively connecting said levers, whereby they will be operated pivotally in unison. 80

3. In a device of the kind described and in combination, a foot-operated rod, a throttle rod, a pair of bell-crank levers each connected to one of said rods and adapted to pivot in mutually transverse planes, and link 85 means connecting both of said levers whereby movement imparted to one will be transmitted to the other, said link having ball ends adapted to engage in sockets at the ends of said bell-crank levers so as to give 90 a universal movement therebetween.

4. In a device of the kind described and in combination, with the throttle rod and steering post throttle arm of a motor vehicle, an accelerator comprising a pair of cooperating parts adapted to be clamped about 95 said steering post, means for clamping said parts together, means for rigidly spacing said clamping parts, said spacing means being arranged intermediate said pair of cooperating parts and encircling said clamping means, both of said cooperating parts being adapted to bear against the throttle arm which limits its movement in one direction, and a spacing collar at the opposite 100 end of said cooperating part and adapted to limit its movement in the opposite direction. 105

5. In a device of the kind described and in combination with the throttle rod and steering post throttle arm of a motor vehicle, an accelerator comprising a pair of cooperating parts adapted to be clamped about 110 said steering post, screws for clamping said parts together, bushings encircling said screws and arranged between said pair of cooperating parts for rigidly spacing said parts, cooperating parts being adapted to bear against the throttle arm and a spacing collar at the opposite end of said cooperating parts, whereby movement thereof 115 in opposite direction is prevented. 120

6. In a device of the kind described and in combination with the throttle rod and the steering post throttle arm of a motor vehicle, an accelerator adapted to be carried by 125 said post and comprising a reciprocating foot rod, and means for transmitting the movement of said foot rod to said throttle rod, said means comprising a pair of bell-crank 130

- levers, one connected to said foot rod and the other to said throttle rod, said bell-crank levers being pivoted so as to move in mutually transverse planes, connecting means 5 between said bell-crank levers whereby the pivotal movement of one will be transmitted to pivotally move the other, one of said bell-cranks having an offset portion thereon normally free of but in the path of movement 10 of the throttle arm, whereby said throttle rod may be moved by said throttle arm as well as by said foot rod.
7. In a device of the kind described and in combination with the throttle rod and steering post throttle arm of a motor vehicle, an accelerator adapted to be carried by said post and comprising a reciprocatory foot rod, and means for transmitting the movement of said foot rod to said throttle 15 rod, said means comprising a pair of bell crank levers, one connected to said foot rod and the other to said throttle rod said bell crank lever being pivoted so as to move in mutually transverse planes, universally 20 movable connecting means between and connecting said bell-crank levers whereby the pivotal movement of one will be transmitted to pivotally move the other, one of said bell-cranks having an offset portion 25 thereon adjacent the steering post, and in the path of movement of the throttle arm, so as to be engageable therewith and moved thereby.
8. In combination with the throttle rod, and steering post throttle arm of a motor vehicle, an accelerator adapted to be carried by said post and comprising a reciprocatory foot rod, and means for transmitting the movement thereof to said throttle rod, said 30 means comprising a pair of bell crank levers mounted so as to be pivotally movable in mutually transverse planes, a link connecting said bell crank levers, ball and socket means at the interconnected end of said link and levers whereby a universal movement 35 therebetween is permitted, and means for automatically returning said parts to their normal position after the operation thereof.
9. In combination with the throttle rod, and steering post throttle arm of a motor vehicle, an accelerator adapted to be carried by said post and comprising a pair of bell crank levers pivotally movable in mutually transverse planes, a foot rod having one end 40 connected to one of said bell crank levers, a throttle rod connected to the other of said bell-crank levers, sockets at the ends of the 45 other arms of said bell-crank levers, a link having ball ends adapted to fit into said sockets to operatively connect said bell-crank levers whereby they may be simultaneously pivoted in mutually transverse planes and abutment means on one of said bell crank levers, adapted to be engaged by said throttle arm whereby the throttle may 50 be controlled at said steering post.
10. In combination with the throttle rod and steering post throttle arm of a motor vehicle, a pair of accelerator supports adapted to be carried on the steering post, a pair of bell-crank levers mounted on said supports so as to be pivotally movable in mutually transverse planes, connecting means between said bell-crank levers connected to one arm of each of said bell-crank 55 levers, whereby a pivotal movement of one of said bell-crank levers will be transmitted to pivotally move the other of said bell-crank levers, a foot rod connected to one of said bell-cranks, said throttle arm connected 60 to the other of said bell-cranks, means for adjustably connecting said throttle rod to said bell crank levers, and means for adjustably connecting said foot rod to the other of said bell-crank levers.
11. In combination with the throttle rod and steering post throttle arm of a motor vehicle, a pair of accelerator supports adapted to be carried on the steering post, a pair of bell-crank levers mounted on said supports so as to be pivotally movable in mutually transverse planes, connecting means between said bell crank levers connected to one arm of each of said bell-crank levers whereby a pivotal movement of one of said bell-crank levers will be transmitted to pivotally 65 move the other of said bell crank levers, a swivel on one of said bell-cranks, rotatable on an axis parallel to the pivotal axis of said bell-crank, a foot rod secured to said swivel 70 and rotatably adjustable thereon in an axis transverse to said swivel axis, means for adjustably connecting said throttle rod to the other of said bell-crank levers, and means for adjustably connecting the foot rod to 75 said swivel.
- In testimony whereof, I have hereunto signed my name in the presence of two subscribing witnesses.
